UNITED STATES PATENT OFFICE.

CHARLES B. McCALLUM, OF OAKLAND, CALIFORNIA.

GROUND FOR PLASTERING.

Application filed May 19, 1924. Serial No. 714,279.

To all whom it may concern:

Be it known that I, CHARLES B. McCALLUM, a citizen of the United States, residing at Oakland, in the county of Alameda and State of California, have invented certain new and useful Improvements in Grounds for Plastering, of which the following is a specification.

My invention relates to grounds employed in the art of plastering, and more particularly to removable grounds adapted to be used over and over again.

Present grounds consist of a strip of wood nailed permanently in place about a door, window or other opening in building construction. Eventually plaster is floated on the furred wall flush with the grounds, the distance from face to face of the oppositely positioned grounds determining the thickness of the wall. Between the said positioned grounds is the studding, which is commonly of rough sawed lumber and of nominal width. The studding with its varying width and rough edges, in combination with the sawed grounds determine the parallelism and nominal thickness of the wall.

Therefore, having the above in view, an important object of my invention is to determine walls about an opening having parallel surfaces thereat, and of constant thickness, using the same studding above cited but eliminating the said grounds.

Another important object is to provide metallic grounds for determining the said parallel surfaces and thickness of the wall.

A further object is that the grounds of my invention shall be removable and adaptable for further use.

And a still further object is the provision of a ground in the form of a plate having means to quickly and accurately position the same, and making provision for the quick removal thereof after the plaster has set a little.

A wall produced by the aid of my grounds has for its ultimate object, openings throughout the building such that the jamb, casing and other woodwork can come from the mill as finished products and be immediately secured about the opening without any cutting and fitting because of said constant width and parallelism.

A ground of my construction will admit correction in alignment of several openings as regards to the face of the walls in continuity, as a corridor for example.

For an applied illustration of my invention, I have shown it in the accompanying drawing in combination with a door opening, and in which drawing:

Figure 1 is a front elevation of a ground constructed in accordance with the invention.

Figure 2 is a side view of it applied to the door-opening of a wall; some studding, lathing and plastered finished wall is here shown.

Figure 3 is a horizontal section, on an enlarged scale, on the line 3—3 of Fig. 2 and shows to advantage the ground in fixed relation to the wall at the doorway.

Figure 4 is a view similar to Fig. 3 but shows the ground as a flat plate, and Fig. 5 is also a similar view and introduced simply to show the present wood ground assembly at such an opening.

Figure 6 is a fragmentary view of Fig. 1 showing an enlargement of one of the securing holes.

Adverting to the drawing and figures thereof: the numeral 7 indicates my ground and in Figs. 1 to 3 it is shown as light plate rolled or otherwise formed to an accurate form and width with true and parallel outside faces 8. The width of the channeled ground is that of the nominal desired studding 9, plus the thickness of the wood lathing 10 and the nominal thickness of the plaster 11. Of course, for definite thickness of walls such as wide and narrow ones, I will have different grounds to correspond with the desired thickness of the finished wall.

The flanges 12 of my channeled ground serve as stiffening ribs to prevent the body from buckling or bending in usage, and the outside faces 8 present a broad guiding surface for floating the plaster or other coating 11 flush therewith.

In Fig. 4 the ground 13 may be of fiber, plate steel or other suitable material, having accurately machined or otherwise formed parallel edges 14, the width of the ground being that of the desired thickness of the wall.

In Fig. 5 the ground 15 is the common well-known wooden strip nailed for permanent securement to the studding 9 as at 16, and the plaster 11 is floated flush therewith.

In all the figures the width of the studding is assumed to be the same, thus, if the nominal width is 4", it might come from

the saw mill as $3\frac{3}{4}$ " or $4\frac{1}{4}$ " or some other width, and the nominal $\frac{3}{4}$ " wood ground may be $\frac{1}{8}$ " wider or narrower, and hence the desired $5\frac{1}{2}$ " wall may actually finish 5" to 6" face to face of plaster.

With my ground and using the same studding and lathing there can be only the width of wall desired and that is the width of the ground, the thickness of the plaster being the compensating element. As previously stated, with the aid of my device a given wall will have a constant width with parallel faces, enabling mill-work for the trimmings of such openings to be accurately positioned with no hand trimming at all of the wall surfaces at such openings.

The manner of positioning and securing my ground in place is unique, and herein resides additional invention. Near the top of each ground, a preferably round hole 17 is determined, such that when the ground is suspended by a nail 18 Fig. 3 or other instrument it will hang perfectly plumb, that is, the outside faces 8, or edges 14 will be in perpendicular planes. Along the body of the ground are additional holes 19 spaced at random for rigidly, and but temporarily, securing the ground to the studding as with common nails 20, Fig. 2. These holes may be elongated as shown clearly at 21, Fig. 6, for the quick detachment of the ground after the plastered and finished wall has set. The removal is accomplished by withdrawing the nail 18 and inserting a pinch-bar (not shown) under the ground in the purposely allowed space 22, Fig. 2, to cause the ground to raise sufficient to clear the head of the nail 20 in the larger bore 23 of the elongated hole 21. The ground may then be detached from the studding and the protruding nails driven therein.

At the top of the ground, a space 24 is left similar to space 22. After the two side grounds are positioned at the doorway, the top ground 25 which may be of flat plate, is

secured to the studding 26 by attaching means similar to that employed in the side grounds, and end spaces are left similar to space 22.

In operation, the frame-work of the wall having been completed including the lathing, my ground is centered and positioned against the studding 9 using the fingers at the edge or a spacing gage, then a nail 18 is driven through the top hole 17 to simply suspend the ground. The ground will assume its perpendicular position and the securing nails 20 may then be driven and the wall made ready for the plaster.

The position of the top hole 17 is very important, and each ground has its hole determined separately by test in the work-room. The hole is not merely placed in the center line, as I have found that materials are not homogeneous, hence, the hole is accurately formed at a found spot such that when the ground is freely suspended on an instrument through the said hole, it will assume a plumb position and its outside faces 8 or edges 14 will be in absolute perpendicular planes.

Having thus described my invention, what I claim as new and desire to secure by Letters Patent is the following:

1. A ground of the character described, comprising a channeled strip of material having parallel flanges and having at an end thereof a hole predetermined in position for suspending the ground plumb.

2. A removable ground for plastered walls, comprising a strip of metal of width to correspond with the desired thickness of the finished wall, said strip having a hole at an end thereof to hang the ground plumb, and the said ground provided with additional holes spaced at random for removably securing the ground to the studding.

In testimony whereof I affix my signature.

CHARLES B. McCALLUM.
